UNITED STATES PATENT OFFICE.

ERASTUS E. WINKLEY, OF LYNN, MASSACHUSETTS.

AUTOMATIC SHOE-MACHINE.

1,218,148.

Specification of Letters Patent.

Patented Mar. 6, 1917.

Application filed September 21, 1912. Serial No. 721,593.

To all whom it may concern:

Be it known that I, ERASTUS E. WINKLEY, a citizen of the United States, residing at Lynn, in the county of Essex and State 5 of Massachusetts, have invented certain new and useful Improvements in Automatic Shoe-Machines; and I do hereby declare the following to be a full, clear, and exact description of the invention, such as will enable others skilled in the art to which it 10 pertains to make and use the same.

The present invention relates to machines for use in the manufacture of boots and shoes.

15 In the method of making welt shoes devised by me the ends of the welt on a welted shoe are butted and an outsole having a rounded heel, a rounded and skived shank and a block forepart, is applied to the welt 20 butted shoe in such manner that the rounded heel registers with the rounded heel of the insole. The ends of the welt and the shank skiving adjacent the heel seat terminate a predetermined distance from the rear 25 ends of the insole and outsole respectively in order that a smooth well fitting joint may be produced between the welt and outsole. Preferably, although not necessarily, the predetermined distance hereinbefore referred 30 to is such that the breast of the heel of the finished shoe bisects the joints between the outsole and the welt as it is found that with this arrangement the pressure of the heel acts to effectively hold the outsole and 35 the welt in their jointed relation. In order to carry out my method of making welt shoes in a commercial manner I have devised a system of automatic machines for rounding and skiving the outsole, for butting the welts 40 and for laying the outsole properly on the welt-butted shoe. In the best form of welt butting machine hereinbefore devised by me the welt butting operation is automatically performed after the welted shoe has been 45 located at the welt butting station by the operative who depends entirely upon his judgment in adjusting the back stop with which the machine is provided so that the ends of the welt may be butted at the proper 50 point. In order to successfully carry out my novel method of making welt shoes it is necessary for the operative to adjust the back stop so that the desired portion of the

shoe bottom, usually the breast line of the insole, will register with the welt butting 55 instrumentalities at the welt butting station. Specifically it is found impossible for an operative to determine by inspection the breast line of a welted shoe and then adjust the back stop in the welt butting machine so 60 that the shoe is located at the welt butting station with the actual breast line of the shoe registering with the welt butting instrumentalities.

The object of the present invention is to 65 produce a welt butting machine by which the welts of shoes of the same size and style may be butted in a uniform manner without requiring the attention of the operative except to place the welted shoe in the machine and remove it therefrom after the completion of the welt butting operation.

To the accomplishment of this object, and such others as may hereinafter appear, the features of the invention relate to certain 75 devices, combinations and arrangements of parts hereinbefore described and then set forth broadly and in detail in the appended claims, which possess advantages which will be apparent to those skilled in the art. 80

The various features of the present invention will be best understood from an inspection of the accompanying drawings illustrating the preferred embodiment of the invention in which, 85

Figure 1 is an elevation of the left side of the machine showing a shoe positioned at the welt butting station for the welt butting operation;

Fig. 2 is a detail in plan of the shoe supporting table and the devices carried thereby;

Fig. 3 is a longitudinal sectional elevation on the line 3—3, Fig. 2, showing a shoe mounted upon the last supporting spindle; 95

Fig. 4 is a front elevation of the shoe supporting table, the devices carried thereby, and the mechanism associated therewith;

Fig. 5 is a sectional elevation on the line 5—5, Fig. 2;

Fig. 6 is a front sectional elevation on the line 6—6, Fig. 2; and

Fig. 7 is a front sectional elevation on the line 7—7, Fig. 2.

The embodiment of the invention illustrated in the drawings is provided with a

stationary welt butting head of the automatic type the construction of which is fully described and illustrated in the United States Letters Patent to E. E. Winkley, 5 1,029,837, June 18, 1912. The welt butting instrumentalities carried by the welt butting head are operated in the same manner as the corresponding welt butting instrumentalities in the patent referred to and, 10 therefore, they need not be described in detail herein as reference may be had to said patent.

In the illustrated embodiment of the invention the work supporting devices are carried upon a table 1 (Figs. 1 and 2) mounted to slide in ways 2, (Figs. 6 and 7), formed in a bed 3 (Fig. 1), projecting forwardly from the supporting frame 4 for the welt butting head 5. The table 1 is held in position upon the bed 3 by cover plates 6 carried by the bed and arranged to over-lap the table 1. The table 1 is automatically moved during the operation of the machine from a position convenient for the insertion and removal of a shoe, which position is herein-after termed for convenience the "jacking station", to a position where the breast line of the shoe is located adjacent the welt butting instrumentalities which position is herein termed for convenience the "welt butting station". To this end the rear end of the table 1 is provided with a bracket 7 (Fig. 3) upon which is pivotally mounted one end of a short link 8 the other end of which is pivoted to an arm 9 (Fig. 1) loosely mounted upon a horizontal rod 10 carried by the frame 4. Pivotally mounted upon the rod 10 is a second arm 11 which is connected by a link 12 with an arm 13 pivoted intermediate its ends on a pin 14 carried by the head 5. The upper end of the arm 13 is provided with a roll 15 which is engaged by a groove formed in a cam 16 carried by a cam shaft 17 journaled in the head 5. The cam shaft 17 is driven from a suitable source of power through a pinion 18, on a driving shaft 19, which meshes with a gear 20 on the shaft 17. In order to actuate the arm 9, when the arm 11 is oscillated on the rod 10 by the connections from the cam 16, the arm 9 carries a perforated lug 21 which embraces a rod 22 carried by a lug 23 formed on the arm 11. The lugs 21 and 23 are normally held in contact by a spring 24 coiled around 55 the rod 22 and interposed between the lug 21 and a suitable adjusting and locking device 25. With the construction described the work supporting table 1 is brought from the shoe jacking station to the welt butting station when the clutch (not shown) which controls the driving shaft 19 is thrown into operation by the operative. After the welt butting operation the work supporting table 1 is returned to the shoe jacking station at 60 65 which time the clutch hereinbefore referred

to is automatically tripped and the machine brought to rest. The provision of the yielding connection between the arms 9 and 11 permits the extent of movement of the table 1 toward the welt butting station to be limited independent of the cam 16 so that the shoe may be variably located at the welt butting station. In the embodiment of the invention illustrated in the drawings the independent means for limiting the extent of movement of the table 1 toward the welt butting station takes the form of a pair of coöperating stops one of which, a stop 26, is carried by the bed 3 (Figs. 3 and 7) and the other one of which, a stop 27, is carried by the sliding table 1 (Fig. 3).

In order to support a shoe the table 1 carries a slide 28 arranged to slide in ways 29, beneath cover plates 30 secured to the table. The slide 28 carries a vertical hollow post 31 which slidably receives a vertical spindle 32 provided at its upper end with a last pin 33 (Fig. 2) arranged to engage the pin socket in a last 34 which carries a lasted and welted shoe (Fig. 3). The supported shoe is normally maintained elevated by a spring 35 coiled around the spindle and interposed between the bottom of the hollow post 31 and a shoulder 36 formed on the spindle. The upward movement of the shoe under the influence of the spring 35 is limited by a plate 37, arranged to engage the heel seat of the shoe. The depending shank 37a of the plate 37 is pivotally mounted between the arms of a yoke 38 on a standard 39 carried by the slide 28. The shank 37a of the plate 37 is provided with a horizontal arm 40 (Fig. 6) which carries a screw 41 the head of which is embraced by a slot 42 formed in a block 43 on the upper end of a vertical rod 44 slidably mounted in lugs 45 and 46 formed on the standard 39. The plate 37 is normally maintained in position to limit the upward movement of the shoe by a spring 47 coiled around the rod 44 and interposed between the lug 45 and a pin 48 on the rod. The pin 48 also acts as a stop and coöperates with the lug 46 to limit the movement of the plate 37 under the influence of the spring 47.

In order to lower the supported shoe and swing the heel seat engaging plate 37 transversely of the shoe to permit the unobstructed removal of the shoe from the last pin 33 and the placement of another shoe thereon the machine at the jacking station is provided with a sliding block 49 (Fig. 4) mounted to slide in vertical ways 50 formed in the bed 3. The block 49 is bifurcated and is mounted on the upper end of a vertical rod 51 which is connected to a treadle and a tension device (neither of which is shown) the construction being such that the block 49 is normally maintained elevated by the tension device but may be depressed against

the tension of the device by the treadle. The arms of the block 49 are provided with horizontal lugs 52 which are arranged, when the shoe is located at the jacking station, above 5 a pin 53 projecting from the opposite sides of a block 54 on the lower end of the spindle 32. When the treadle rod 51 is depressed the lugs 52 engage the projecting ends of the pin 53 and lower the shoe against the 10 tension of the spring 35. To swing the plate 37 transversely of the shoe when the rod 51 is depressed the bed 3 carries a pivoted arm 55 (Fig. 3) which is provided at its free end with a roll 56 arranged in the 15 path of movement of a slot 57 formed in a block 58 carried by the lower end of the heel seat engaging plate rod 44. When the shoe is moved away from the shoe jacking station the arm 55 is supported by a finger 59 (Figs. 20 3 and 4) projecting from a block 60 adjustably mounted on the rod 51. When the shoe is at the shoe jacking station the roll 56 is supported by its engagement with the slot 57. As soon, however, as the block 49 is de- 25 pressed a sufficient distance to strike a screw 61 (Figs. 3 and 4) adjustably carried by the arm 55 the latter is actuated in a direction to lower the rod 44 and thus swing the plate 37 transversely of the shoe. After the shoe 30 is removed from the spindle another shoe is placed thereon and the treadle rod 51 released to the influence of the tension device. As the block 49 rises the plate 37 gradually swings transversely of the shoe under the in- 35 fluence of the spring 47 the construction being such that the plate is repositioned over the heel seat of the shoe as the latter is being elevated so as to limit the upward movement of the shoe under the influence of the 40 spring 35. It is apparent that with this construction the welt crease of shoes of all sizes and styles are uniformly brought into the same plane.

In order to relieve the operative of the 45 duty of adjusting the position of the shoe in an attempt to register the breast line of the shoe with the welt butting instrumentalities at the welt butting station the illustrated embodiment of the invention is provided 50 with mechanism for automatically controlling the independent limiting means comprising the stops 26 and 27 hereinbefore referred to so as to invariably register the 55 breast line of shoes of all sizes and styles with the welt butting instrumentalities at the welt butting station. To this end the machine of the drawings is provided with mechanism for measuring the length of each 60 shoe inserted into the machine and with connections between the length measuring mechanism and the stop 27 for adjusting the latter a distance having the same proportion to the amount of measuring movement of the measuring mechanism as the length of 65 the heel seat bears to the length of the shoe.

With this construction the length of the shoe is measured and the stop 27 adjusted in accordance with the length so determined so that when the table 1 is moved toward the welt butting station the position of the stop 70 27 will be such as to strike the stop 26 and thus limit the rearward movement of the table 1 when the breast line of the shoe has registered with the welt butting instrumentalities. 75

In order that the length of the shoe may be measured the machine of the drawings is provided with a finger 62 arranged to engage the counter of the shoe and with a finger 63 arranged to engage the toe of the 80 shoe (see Figs. 3 and 5). The finger 62 is formed on the upper end of the vertical arm of a bell crank lever 64 (Figs. 2 and 5) pivotally mounted on a standard 65 carried by one of the cover plates 30 on the table 1. 85 The horizontal arm of the bell crank lever 64 is connected by a bent link 66 to one end of a bell crank lever 67 pivoted on a yoked arm 68 carried by the standard 65. The other end of the bell crank lever 67 is provided with a depending finger 69 (Figs. 5 and 6) which is provided with a wedge-shaped end 70 arranged to extend between a pair of cylindrical rolls 71 interposed between the bottom of the slide 28 and a pair 90 of inclined surfaces 72 formed in the table 1. The rolls 71 are normally held jammed between the bottom of the slide 28 and the highest part of the inclines by a pair of springs 73 arranged in recesses 74 formed 95 in the table 1. In order to release the slide 28 so that it may slide freely on the table 1 the rolls 71 are maintained in an inoperative position by the finger 69 which is held between the rolls 71 under the influence of 100 a spring 75 interposed between the upper side of the lever 67 and the bottom of a recess 76 formed in the arm 68.

The finger 63 is formed on the upper end of a bell crank lever 77 pivotally mounted 110 on a standard 78 carried by a slide 79 mounted to slide on the table 1 beneath the cover plates 30 (Figs. 2 and 3). The other arm of the bell crank lever 77 is connected by a link 80 to a two-armed lever 81 pivotally mounted between the arms of a yoke 82 secured to the slide 79. The other arm of the lever 81 is formed as a finger 83 provided with a wedge-shaped end which is normally maintained between a pair of cylindrical rolls 84, arranged between the slide 79 and the table 1, by a spring 85 extending between the lever 81 and the standard 78. When the finger 83 is held between the rolls 84 the slide 79 is free to slide on the table 1. 115 As soon as the finger 83 is withdrawn from between the rolls 84 a pair of springs 86 mounted in recesses on the slide 79 jam the rolls 84 between the table 1 and a pair of inclines 87 on the table 79. 120 125 130

After the shoe is placed in position on the last pin 33 and clamped beneath the heel seat engaging plate 37 the operative moves the slide 28, which carries the last pin 33 and plate 37, and the slide 79, which carries the toe engaging finger 63 toward the heel engaging finger 62 in order to interpose the shoe between the measuring fingers 62 and 63. To this end one of the cover plates 30 on the table 1 carries a two-armed angular lever 88 (Figs. 2 and 7) one arm of which is pivoted to the cover plate and the other end of which is pivoted to the slide 28. Pivoted on the lever 88 at 89 is an arm 90 one end of which is normally held pressed against a perforated lug 91 formed on the lever 88 by a spring 92 coiled around a rod 93, secured to the arm 90 and embraced by the lug 91, and interposed between the lug 91 and a nut 94 on the rod. The other end of the arm 90 is pivoted to one end of a link 95 the other end of which is centrally pivoted on an arm 96 pivoted in turn at one end to a bracket 97 secured to one of the cover plates 30. The other end of the arm 96 is provided with a longitudinal slot 98 which embraces a vertical pin 99 secured to the slide 79. The arm 96 is also connected by a link 100 to a hand lever 101 pivoted at one end on a bracket 102 secured to one of the cover plates 30.

By manipulating the hand lever 101 the slides 28 and 79 may be moved toward the heel engaging finger 62. It will be apparent from an inspection of Fig. 2 that the arrangement of the connections for actuating the slides 28 and 79 will cause them to move differentially toward the heel engaging finger 62 the construction being such that the slide 79 carrying the toe engaging finger 63 will move through a greater distance than the slide 28 carrying the clamped shoe in substantially the ratio 5 to 1.

As soon as the counter of the shoe strikes the finger 62 the finger 69 through the connections described is elevated from between the rolls 71 and the slide 28 is locked to the table 1 by the jamming of the rolls. Continued rearward movement of the slide 79 is permitted by the yielding connection between the lever 88 and arm 90. When the finger 63 strikes the toe of the shoe the finger 63 is elevated and the slide 79 is locked to the table 1 by the jamming of the rolls 84.

In order to control the position of the stop 27 in accordance with the length of the shoe as determined by the length measuring fingers 62 and 63 the stop 27 is carried upon a slide 103 (Figs. 6 and 7) mounted to slide in ways 104 formed in the bottom of the table 1 the slide 103 being retained in position in the ways by cover plates 105 carried by the table and arranged to over-lap the slide. The slide 103 is provided with rack

teeth 106 (Fig. 3) for a portion of its length which are engaged by a pinion 107 carried by a pin 108 on the bracket 7. The pinion 107 meshes with a segment 109 carried by a stub shaft 110 journaled in the bracket 7. One end of the stub shaft 110 carries a depending arm 111 which is pivotally connected through a link 112 to an arm 113 depending from the slide 79 (Fig. 4). With this construction the stop 27 is located in a position determined by the length of the shoe interposed between the measuring fingers 62 and 63. In the embodiment of the invention illustrated in the drawings the connections between the stop 27 and the slide 79 are such that the stop 27 is adjusted by the length measuring movement of the slide 79 in the ratio that the length of the heel seat of the jacked shoe bears to the length of the shoe. That is, the stop 27 is adjusted under the influence of the length measuring mechanism so that when the table 1 is moved toward the welt butting station the stop 27 will contact with the stop 26 and limit the movement of the table when the breast line of the shoe has registered with the welt butting station.

As well known to those skilled in the art shoes are designed in such manner that there is a predetermined ratio between the length of the shoe and the length of the heel seat. This ratio, however, varies for the different sizes and styles of shoes. In order therefore that the machine may invariably position the breast line of shoes of all sizes and styles at the welt butting station the connections between the stop 27 and the slide 79 are adjustable to permit the ratio between the movements of the stop 27 and the slide 79 to correspond with the known ratio between the length of the heel seat and the length of the shoe of the size and style which the operative desires to insert into the machine. To this end the arm 111 is provided with a segmental slot 114 (Fig. 3) which embraces a pin 115 forming the pivotal connection between the arm 111 and the link 112. By varying the position of the pin 115 longitudinally of the slot 114 the ratio between the movements of the stop 27 and the slide 79 may be varied as desired. To guide the operative in changing the ratio the arm 111 is provided with a scale 116 which registers with an index 117 on the link 112 to indicate the desired ratio. To lock the arm 111 and link 112 in their adjusted position the link 112 carries a pivotally mounted spring pressed plunger 118 the head of which is arranged to engage any one of a series of holes 119 formed in the arm 111.

While the invention has been explained in connection with my system of automatic machines for carrying out my method of making welt shoes it will be apparent to those skilled in the art that a machine embodying

the features of the present invention may be used to butt the welts on welted shoes in factories where my method of making welted shoes is not employed. Many shoe manufacturers do not appreciate the importance of positioning the joints between the welt and the outsole beneath the breast of the heel in the finished shoe. Others appreciate the importance of holding the outsole and welt in jointed relation but take the extreme view that the forward nail at each breast corner of the heel in the finished shoe should penetrate the outsole and the welt at the jointed points. Still others while employing my method incorporate freak heels in their shoes. The lengths of these heels have no relation to the lengths of the heel seats on the outsoles so that the breast of the heels do not register with the designed breast line on the outsoles. To adapt the machine to the varying conditions in the different shoe factories the illustrated embodiment of the invention is provided with an adjustment for arbitrarily changing the point at which the welt is butted. To this end the stop 26 is provided with wings 120 (Fig. 7) which slide over a plate 121 on the bed 3 and also with a block 122 which slides in a slot 123 formed in the plate 121. The stop 26 is clamped in adjusted position by a bolt 124, carried by the block 122, which is arranged to jam a washer 125 loosely carried by the shank of the bolt between the bottom of the plate 121 and the head of the bolt. To aid the operative in making the adjustment the plate 121 is provided with a scale 126 (Fig. 3) and the stop 26 with an index 127 to indicate the desired position of adjustment away from the standard position.

The mode of operation of the embodiment of the invention illustrated in the drawings may be briefly described as follows: During the time that the welt butting instrumentalities are thrown out of operation the table 1 carrying the work supporting devices is held stationary at the shoe jacking station. To remove the welt butted shoe the operative first throws the handle 101 to the right (Fig. 2) thereby separating the length measuring fingers 62 and 63. The treadle rod 51 is then depressed which lowers the spindle 32 and swings the plate 37 transversely of the shoe thus permitting the unobstructed removal of the welt butted shoe and its replacement by another shoe upon the last supporting pin 33. When the new shoe is placed in position upon the pin 33 the operative first releases the treadle rod 51 to permit the springs 35 and 47 to elevate the shoe and swing the plate 37 into its operative position the construction being such that the plate 37 is returned to its operative position in time to limit the upward movement of the shoe under the influence of the spring 35. The operative next throws the handle 101 to the

left (Fig. 2) in order to interpose the shoe between the heel engaging finger 62 and the toe engaging finger 63 and thus measure the length of the shoe. The measuring movement of the finger 63 also adjusts the position of the stop 27 on the table 1 the movement of the stop 27 being proportional to the length measuring movement of the finger 63 in the known ratio that the length of the heel seat on the measured shoe bears to the length of the shoe. The operative now throws in the clutch which controls the main driving shaft 19. The table 1, carrying the shoe, is then withdrawn from the shoe jacking station and moved toward the welt butting station until the stop 27 strikes the stop 26. The table is then held stationary with the breast line of the shoe registering with the welt butting instrumentalities at the welt butting station. The cycle of operations fully described in the patent hereinbefore referred to now follows whereby the welt is automatically butted. At the end of the cycle of operations involved in the automatic welt butting operation the table 1 is returned to the shoe jacking station, the clutch is automatically tripped and the machine is brought to rest.

While the invention has been illustrated and explained in connection with a machine for butting welts it will be apparent to those skilled in the art that certain features of construction may be advantageously embodied in other machines for operating on partially finished or finished shoes.

It will also be clear to those skilled in this class of machines, with the general objects of the present invention in view, that changes may be made in the details of structure, the described and illustrated embodiment thereof being intended as an exploitation of its underlying essentials, the features whereof are definitely stated in their true scope in the claims herewith.

What is claimed as new is:

1. A welt butting machine, having, in combination, welt butting means at a welt butting station, and automatic means for invariably presenting a similar portion of the bottoms of shoes of different sizes at the welt butting station for the operation of said means at a like point on all shoes, substantially as described.
2. A welt butting machine, having, in combination, welt butting means at a welt butting station, and automatic means for invariably presenting the welt crease, at a similar point in the length of shoes of different sizes in the plane of operation of said means, at the welt butting station, substantially as described.
3. An automatic shoe machine, having, in combination, an operating tool, and mechanism controlled by the length of the shoe operated upon operating automatically to

determine the location of the shoe relatively to the operating tool, substantially as described.

4. An automatic shoe machine, having, in combination, an operating tool, mechanism controlled by the length of the shoe operated upon operating automatically to determine the location of the shoe relatively to the operating tool, and means for causing a departure in the relative location of the shoe and tool determined by said mechanism, substantially as described.

5. A welt butting machine, having, in combination, welt butting means at a welt butting station, a shoe support normally at a shoe jacking station, mechanism adapted to actuate the shoe support to and fro between the stations, and independent means for varying the distance through which the shoe support travels in moving toward one of the stations under the influence of said mechanism, substantially as described.

6. A welt butting machine, having, in combination, welt butting means, a shoe supporting jack movable toward and from the welt butting means, means for limiting the extent of movement of the jack toward said means, and mechanism for automatically adjusting said limiting means, substantially as described.

7. A welt butting machine, having, in combination, welt butting means, a shoe supporting jack movable toward and from the welt butting means, means for limiting the extent of movement of the jack toward said means, automatic mechanism controlled by the size of the shoe being operated on for adjusting said limiting means, and means permitting manual adjustment of said automatic mechanism, substantially as described.

8. A welt butting machine, having, in combination, welt butting means, a shoe supporting jack movable toward and from the welt butting means, means for limiting the extent of movement of the jack toward said means, automatic mechanism controlled by the size of the shoe being operated on for adjusting said limiting means, means permitting manual adjustment of said automatic mechanism, and additional means permitting manual adjustment of said limiting means, substantially as described.

9. A welt butting machine, having, in combination, welt butting means at a welt butting station, a shoe supporting jack at a shoe jacking station, mechanism for moving the jack from the shoe jacking station toward the welt butting station, means for limiting the extent of such movement, and automatic mechanism controlled by the size of the shoe being operated on for adjusting said limiting means, substantially as described.

10. A welt butting machine, having, in combination, welt butting means, a shoe sup-

porting jack movable toward and from said means, mechanism for measuring the length of a shoe on the jack, means for limiting the extent of movement of the jack toward said means, and connections between the measuring mechanism and the limiting means for adjusting the latter a distance proportional to the movement of the former, substantially as described.

11. A welt butting machine, having, in combination, welt butting means, a shoe supporting jack movable toward and from said means, mechanism for measuring the length of a shoe on the jack, means for limiting the extent of movement of the jack toward said means, and connections between the measuring mechanism and the limiting means for adjusting the latter by the movement of the former in the known ratio that the length of the heel seat bears to the length of the shoe, substantially as described.

12. A welt butting machine, having, in combination, welt butting means, a shoe supporting jack movable toward and from said means, mechanism for measuring the length of a shoe on the jack, means for limiting the extent of movement of the jack toward said means, connections between the measuring mechanism and the limiting means for adjusting the latter by the movement of the former in the known ratio that the length of the heel seat bears to the length of the shoe, and means for adjusting said connections in accordance with variations in the desired ratio to adapt the machine to operate on different sizes and styles of shoes, substantially as described.

13. A welt butting machine, having, in combination, welt butting means, a shoe supporting jack movable toward and from said means, mechanism for measuring the length of a shoe on the jack, means for limiting the extent of movement of the jack toward said means, connections between the measuring mechanism and the limiting means for adjusting the latter a distance directly proportionate to the movement of the former, and additional means for adjusting said limiting means to arbitrarily change the point at which the movement of the jack is limited, substantially as described.

14. A welt butting machine, having, in combination, welt butting means, a shoe supporting jack movable toward and from said means, mechanism for measuring the length of a shoe on the jack, means for limiting the extent of movement of the jack toward said means, connections between the measuring mechanism and the limiting means for adjusting the latter by the movement of the former in the known ratio that the length of the heel seat bears to the length of the shoe, means for adjusting said connections in accordance with variations in the desired ratio to adapt the machine to operate

on different sizes and styles of shoes; and additional means for adjusting said limiting means to arbitrarily change the point at which the movement of the jack is limited, substantially as described.

5 15. A machine for operating upon shoes, having, in combination, a table having a heel engaging finger mounted thereon, a last supporting slide and a toe engaging finger supporting slide, and means for differentially moving the slides toward the heel engaging finger, substantially as described.

10 16. A machine for operating upon shoes, having, in combination, a table having, a heel engaging finger mounted thereon, a last supporting slide and a toe engaging finger supporting slide, means for differentially moving the slides toward the heel engaging finger, and means controlled by the fingers 20 for locking the slides from movement, substantially as described.

15 17. A machine for operating upon shoes, having, in combination, a last supporting spindle for supporting a last carrying the work, a heel seat engaging device, and common means for lowering the spindle and swinging the heel seat device to permit the unobstructed insertion and removal of the work, substantially as described.

20 18. A machine for operating upon shoes, having, in combination, a shoe support, and means for bringing the soles of shoes of all sizes mounted on the support invariably into the same plane comprising a plate carried 25 by the shoe support, and means for moving said plate widthwise of the shoe into and out of operative position, substantially as described.

30 19. A welt butting machine, having, in combination, welt butting means at a welt butting station, and automatic means for invariably presenting a similar portion of the bottoms of shoes of different sizes at the welt butting station both vertically and horizontally for the operation of said means thereon, substantially as described.

35 20. A welt butting machine, having, in combination, a guideway, a welt butting station at one end of the guideway, a shoe jacking station at the other end of the guideway, a shoe supporting jack movable in said guideway between said stations, mechanism for moving the jack from the shoe jacking station toward the welt butting station, 55 means for limiting the extent of such movement, and automatic mechanism controlled by the size of the shoe being operated on for adjusting said limiting means, substantially as described.

40 21. An automatic shoe machine, having, in combination, an operating tool, means for moving the shoe toward the tool for the operation of the tool thereon, and automatic mechanism controlled by the size of the shoe 45 being operated on for determining the ex-

tent of movement of the shoe relatively to the operating tool, substantially as described.

22. An automatic shoe machine, having, in combination, an operating tool, a shoe support, means for measuring the size of the shoe on the support while out of operative position with relation to the tool, and mechanism controlled by the measured size of the shoe operating automatically to determine 70 the operative position of the shoe relatively to the operating tool, substantially as described.

23. An automatic shoe machine, having, in combination, an operating tool, a shoe support, means for measuring the size of the shoe on the support while out of operative position with relation to the tool, mechanism controlled by the measured size of the shoe operating automatically to determine the 80 operative position of the shoe relatively to the operating tool, and means for causing a departure in the relative location of the shoe and tool determined by said mechanism, substantially as described.

24. An automatic shoe machine, having, in combination, an operating tool, a shoe support, means for measuring the size of the shoe on the support while out of operative position with relation to the tool, a stop to 90 determine the position of the shoe relatively to the operating tool, and means for varying the position of said stop controlled by the operation of the size measuring means, substantially as described.

25. In a shoe machine, a last support movable to effect displacement of the last in a direction transverse to the plane of the heel seat, a device for engaging and holding shoe stock upon the bottom of the last, said device being movable from an idle position to a position over the bottom of the last, and means for effecting said movement of the device upon an initial movement of the support, the support being movable subsequently to carry the last farther in the direction of the stock engaging portion of the device to clamp the stock effectively upon the last, substantially as described.

26. A machine for operating upon shoes, having, in combination, a last supporting spindle for supporting a last carrying the work, a heel seat engaging device, and means for concurrently retracting the spindle and swinging the heel seat device to permit the 115 unobstructed insertion and removal of the work, substantially as described.

27. A shoe machine, having, in combination, a movable last spindle for supporting a last carrying the work, a coöperating heel 125 seat clamping device movable from an idle position to a clamping position over the bottom of the last, and mechanism for concurrently advancing said spindle and locating said device over the heel seat in 130

position to clamp the work, substantially as described.

28. A shoe machine, having, in combination, a last spindle for supporting a last carrying the work, a heel seat engaging device movable from a position over the last to an idle position, means for retracting the last spindle, and means controlled by the move-

ment of the spindle retracting means for moving said heel seat device to its idle position to permit positioning of the work on the spindle, substantially as described. 10
